CHARGING MACHINE FOR BOTTLE
MANUFACTUREHeinrich Severin, Sasbach, near Achern, Baden,
GermanyApplication December 5, 1932, Serial No. 645,791
In Germany December 16, 1931

10 Claims. (Cl. 198—31)

This invention relates to a charging machine which receives from the general transporting means the bottles accruing at a glass furnace and deposits them in an upright position entirely without shock in an annealing furnace in the usual manner.

The bottles may vary in diameter within wide limits, which are only dependent upon the construction of the machine and the breadth of the belt conveyors. It is also immaterial whether the bottles to be stacked are round or angular, and whether they are large or small. The machine may be built for an annealing furnace of any breadth and is adjustable within wide limits in this respect. The maximum output of the machine described in detail below amounts to thirty bottles per minute. If the requirements exceed this figure, which corresponds to an output of about forty-three thousand bottles per day, it is advisable to adopt a construction comprising three distributor arms or to provide each transport arm with two or more transport tracks which can be charged one after the other, and bring the bottles into a common erecting device, tipping trough or the like.

One form of construction of the invention, comprising two distributor arms, with one transporting track on each distributor arm, is illustrated by way of example in the accompanying drawings, in which

Figure 1 is a side view,

Figure 2 is a side section through the centre,

Figure 3 is a view from above, with half the cover plate of the machine base removed,

Figure 4 is a view from the rear, with half the cover plate and the drive omitted, and

Figures 5, 6 and 7 show the erecting head serving for setting up the bottles with the displaceable tipping trough, Figure 5 being a side view with the tilting trough rocked up, Figure 6 a plan, and Figure 7 a section on the line 7—7 in Figure 5. For the sake of clearness, only those parts that are necessary for the comprehension of the method of working of the machine are herein-after referred to by reference numerals, and specified in detail.

The machine illustrated in Figures 1 to 4 comprises two distributor arms 5 and 5a, which are substantially duplicates of one another. The various parts of the distributor arm 5a shown in Figure 1, in the lower part of Figure 3 and the right-hand half of Figure 4 are distinguished, by the addition of the letter *a* to the reference numeral, from the corresponding parts of the distributor arm 5, shown in Figure 2, in the upper

part of Figure 3 and the left-hand half of Figure 4.

The charging machine consists of a base 1, running to the furnace on rails and accurately adjustable in height. The base carries in its upper cover plate two slide guides 2 and 2a, in which slides 3 and 3a respectively are guided.

At the end of the slides facing the furnace the two distributor arms 5 and 5a are so supported in frames 4 and 4a as to be horizontally rotatable about pivots 6 and 6a.

At the lower end of the pivots 6 and 6a of these arms 5 and 5a are fixed levers 7 and 7a respectively, which are guided with rollers 8 and 8a fitted to the other ends thereof in longitudinal guides 9 and 9a in slide pieces 10 and 10a respectively.

These slide pieces are guided upon pairs of slide rods 11 and 11a fixed in the base, and have on their under side rollers 12 and 12a, which are pushed to and fro by worms 13 and 13a rotating to right or left according to the movement of the arms.

The slides 3 and 3a carry belt conveyors 14 and 14a and the distributor arms 5 and 5a carry belt conveyors 15 and 15a serving for the rapid feeding of the bottles.

At the ends of the distributor arms 5 and 5a projecting into the annealing furnace are suspended depositing or erecting heads 16 and 16a respectively, as shown in Figures 5, 6 and 7.

The depositing head 16 consists of a tipping trough 17, displaceable forwards in a horizontal direction, a tipping frame 20, which is supported by pivots 21 in side plates 19, and brackets 22 for the bottom plate 24 swinging about a pivot 23. The bottom plate is fixedly connected with an abutment lever 25.

The tipping frame 20 holds at both ends two slide rods 26, upon which two slide shoes 27 connected by a plate 28 are slid to and fro. The slide shoes are guided by rollers 18 in slots in the side plates 19 of the depositing head.

This connecting plate 28 comprises guides 29, in which there slide four round rods 30, to the ends of which the tipping trough 17 is secured by means of a holding plate 34.

Upon the tipping frame 20 is fitted a bracket 31. In this bracket 31 and the cover plate 32 of the tipping frame 20 are supported two pivot bolts 33, to which are secured on the one hand two wings 34, and on the other hand two small levers 35. These levers are guided by suitable pins 36 in slots 37 in the connecting plate 28, 55

and when these are displaced the wings 34 open, and when they are slid back the wings close.

To the connecting plate 28 is also fixedly connected the bearing for the pivot bolt 38, to which is attached a guiding link 39 pivoted to a connecting rod 40 by a bolt 41.

The entire depositing head can be exchanged at any time in a few minutes after releasing the bolt 38 or the bolt 41 from the guiding link 39 at the conclusion of an operating period, simply by lifting off one head and hanging on another.

The depositing head 16a is identical with the depositing head 16 in construction and operation, its various parts being distinguished from those of the depositing head 16 by the addition of the letter *a* to the reference numerals.

Above the end of the machine base remote from the annealing furnace, is erected a feeding conveyor 42, which is directly connected with the general conveying means running from the glass furnace. At the discharge end of this feeding conveyor switch points 43 are provided, which are pivoted to a vertical shaft 44, and which distribute the bottles, according to their position, to the belt conveyors 14 and 14a of the slides 3 and 3a through two chutes 45 and 45a.

Between these switching points 43 and the end of the feeding conveyor 42, an arm 47 provided with a catch 46 is so suspended as to be able to swing vertically. With the catch 46 there engages a horizontal arm 49, which is supported at 48, and which is provided with a pawl hook 51 carrying a roller 50 of material which is a bad conductor of heat. To the arm 49 is secured at its pivotal point a mercury tilting contact 52. The arm 49 also has an abutment 53, against which the end of a thrust rod 54 is directed.

The drive for the whole of this apparatus is obtained from an electric motor 55, but may alternatively, where conditions permit, be obtained from the motor of the annealing furnace, in such a way that the forward displacement of the annealing furnace belt conveyor 56 is positively controlled by the charging machine. The shaft 57 of the motor 55 drives through counter-shaft gearing 58 a main shaft 59, upon which are mounted fast all those eccentric sheaves and cam discs which influence the distribution of the bottles accruing to the distributor arms, the lateral advance of the arms, with the depositing head, and the depositing of the bottles.

Loosely grooved on to this driving shaft are two sleeves 60 and 60a, which, by means of two eccentric sheaves or cam discs 61 and 62 secured to the sleeve 60 and two eccentric sheaves or cam discs 61a and 62a secured to the sleeve 60a, determine the forward and backward movement of the slides 3 and 3a, and therefore of the distributor arms and of the depositing heads, as well as the reversing points in the lateral displacement of the latter.

The coupling between the shaft 59 and the sleeves 60 and 60a is effected in the following manner. Upon the shaft 59 are mounted two discs 63 and 63a. Each of these discs carries a number of driving pins, eight in the present instance, adapted to mesh with star wheels mounted fast upon shafts. The driving pins only occupy half the circumference of the disc in each instance, and are so arranged that while the pins 64 on the disc 63 are driving the star wheel 65 and its shaft 66, the pins 64a on the disc 63a are out of engagement with the star

wheel 65a, so that the shaft 66a remains stationary, and conversely. Hence the shafts 66 and 66a are driven intermittently and alternately.

These shafts, through toothed wheels 67 and 67a mounted fast thereon and various transmissions 68 and 68a, actuate toothed wheels 69 and 69a mounted fast upon the sleeve, so that the eccentric sheaves and cam discs 61 and 61a, 62 and 62a, mounted fast upon the sleeve, also advance intermittently from time to time through a distance determined by the transmission ratio, and then come to a standstill again until a further impulse is imparted by the pin wheel gearing, this movement occurring at the right hand and left hand sides of the machine alternately. There are furthermore mounted upon each of the shafts 66 and 66a to which the star wheels 65 and 65a are secured, two toothed wheels 70 and 70a, 71 and 71a. These mesh, in one case directly and in the other case with reversal of the direction of rotation by the interposition of a pinion 72 or 72a, with the toothed wheels 74 and 74a, 75 and 75a, mounted loose upon the shafts 73 and 73a. Upon the shafts 73 and 73a there slide dog clutches 76 and 76a, which rotate the shaft either in a clockwise or in an anti-clockwise direction according to the position of the clutch. The shafts 73 and 73a, through the toothed wheels 77 and 77a mounted fast thereon and the various transmission devices 78 and 78a, drive the shafts 79 and 79a upon which are mounted fast the worms 13 and 13a, and effect both the lateral displacement, and, by altering the direction of rotation, a reversal of the direction of movement, of the rollers 12 and 12a guided in the worms 13 and 13a, and therefore of the levers 7 and 7a of the distributing arms and of the depositing heads 16 and 16a.

The motor shaft 57 drives through bevel gearing 80 a vertical shaft 81 and a bevel wheel 82, and through the latter a horizontal shaft 83, from which the driving of the feeder 42 and the slide conveyors 14 and 14a is effected by chain transmission. The driving of the band conveyors 15 and 15a of the distributor arms is effected through the medium of chains 84 and 84a, actuated by horizontal shafts 86 and 86a, splined in the hubs of bevel wheels 85 and 85a meshing with bevel wheels mounted fast on the transverse shaft 83.

Behind the bevel gear 80 there is fitted into the driving shaft 57, an electromagnetic clutch 87, through which the motor shaft 57 drives the countershaft gearing 58 of the main driving shaft 59, the switching of this clutch is effected primarily by the mercury contact 52 and transiently by a short sliding contact 99, fitted to one of the eccentric sheaves.

This machine operates in the following manner:—

Of the bottles that pass out of the main transporting means onto the feeding conveyor 42 the first strikes against the pendulum 47, releases the catch 46, and slides through underneath the roller 50 of the pawl lever 49, is guided by the switch points 43 to the slide conveyor 14, and is fed by the latter to the belt conveyor 15 of the distributor arm 5, where it slips into the tipping trough 17 of the depositing head, which is then in the nearly horizontal position shown in Figures 1, 5, 6 and 7. As soon as the bottle has released the catch 46, and the pawl lever 49 has fallen down, the circuit is closed by the tilting of the mercury contact 52, and the electromagnetic clutch 87 has set the driving shaft 59 in rotation.

through the medium of the transmission gear 59. The pin gear 64 of the disc 63 now engages with the teeth of the star wheel 65 and rotates, with the shaft 66, the various toothed wheels 67, 5 70 and 71, the sleeve 60, and the eccentric 61 mounted fast thereon, some distance forwards. This eccentric controls the advance and the retraction, which starts at the point of reversal, of the slide 3, the movement of rapid retraction being effected under the pull of a spring, while the forward movement is obtained from a lever 89 by means of a connecting rod 88. According as the connecting rods 88 and 88a are pivoted in one or other of the holes provided at the upper 10 15 ends of the levers 89 and 89a the amplitude of the forward thrust varies so as to adapt the movement to the average diameter of the bottles to be introduced.

Furthermore, by the rotation of the star wheel shaft 66, the two toothed wheels 74 and 75 mounted loose upon the shaft 73 are rotated in opposite directions. According as one or the other is connected by the dog clutch 76 with the shaft 73 and its counter-shafts 78, the worm 13 revolves 20 25 a little further each time either in one direction or the other.

The reversal of the direction, which is always effected when a row of bottles is completely deposited, is effected by displacing the dog clutch 30 35 76, this displacement being controlled by the eccentric sheave 62a likewise mounted fast upon the sleeve 69a, by means of the lever mechanism 90a, the eccentric sheave on the right hand side of the machine in this case controlling the clutch 35 on the left hand side, and conversely.

By suitably selecting the pitch of the dog clutch in relation to the pitch of the star wheel 65, the result is obtained that every time the dog clutch is reversed, a tooth on one side positively 40 45 stands exactly opposite to a space on the other side. It will be evident that the further the star wheel 65 is rotated upon its shaft 66 the greater will be the forward feed of the worm.

In a charging machine of the construction illustrated 45 50 55 the eight driving pins of one half of the discs 63 and 63a, with a transmission ratio of 1:2, rotate the star wheels 65 and 65a through one complete revolution, which corresponds to a lateral movement of the distributor arm and depositing head amounting to 80 millimetres; or in other words the machine is built, in its present construction, for the depositing of bottles having a maximum average diameter of 80 millimetres. If the diameter is greater than 80 millimetres, 55 60 65 which would only occur in quite exceptional cases, the transmission ratio of the pin gearing would have to be taken correspondingly higher, which can be effected without difficulty by changing the two discs and wheels.

In general, however, it will be sufficient to provide for a maximum average diameter of the bottles accruing from the furnace of 80 millimetres, and in most cases it will be less than 80 millimetres. Just as, in such cases, the forward feeding of the slide is regulated by suitably diminishing the effective length of the arm of the lever 89, the smaller bottle diameters, which involve a smaller lateral advance of the depositing head, can be allowed for by providing a smaller number of driving pins than the existing eight on the discs 63 and 63a. It will be immediately obvious that if eight driving pins effect one complete revolution of the star wheel 65 or 65a, and therefore a lateral advance of the depositing head amounting to 80 millimetres, seven driving pins will only

produce seven-eights of a revolution of the star wheel 65 or 65a and an advance of 70 millimetres, six driving pins will produce an advance of 60 millimetres, five an advance of only 50 millimetres, and so forth. According to the average diameter of the bottles to be deposited, therefore, only the number of driving pins necessary for this average diameter need be provided in the discs 63 and 63a, each driving pin corresponding to an advance of 1 centimetre.

If smaller differences are desired, these are easily obtainable at any time by making the pitch of the pin gearing finer.

The speed of revolution of the shaft 59 is so related to the speed of travel of the belt conveyors 14, 14a and 15, 15a that a bottle travels from the pendulum lever 47 to the tipping trough 17 of the depositing device while the shaft 59 is executing nearly half a revolution. By the time this half revolution is terminated, an eccentric 91 mounted fast thereon, by means of a connecting rod 54, has returned the pawl lever 49 into its original position in the catch 46 again. The mercury contact 52 is thereby returned to a horizontal position and interrupted. The electromagnetic 20 25 30 clutch 67 is disengaged, and, while the motor 55 of the band conveyors 12, 14, 14a, 15 and 15a continues to run, the driving shaft 59 is stationary until a second bottle releases the catch 46 and repeats the series of operations previously described on the other side of the machine. While now this second bottle, with steady advance of its distributor arm 5a is fed forwards and sideways to its tipping trough 11a, the first distributor arm 5 is stationary, and the bottle is 35 40 45 deposited in an upright position upon the place allotted to it. For this purpose the connecting rod 40 under spring pressure is slid forward. By the guiding link 39 the tipping frame 20 is tilted and takes up a horizontal position, as shown in Figure 2, the rollers 18 of the slide shoes 21 rolling upward along the segmental dots in the side plates 19. Now upon further advance the slide shoes, with the connecting plate 28, are pushed forward upon their slide rods 26, as a result of which the two levers 35, and therefore the wings 34, are 50 55 60 65 tipping trough 17a, and the mercury contact 52 has been returned into a horizontal position and disengaged.

Now it is by no means contemplated, however, to interrupt the running of the machine and bring it to a standstill every time a bottle is deposited, thereby necessitating a fresh start every time. Instead of this the speed of revolution of the continuous current motor 55 is so regulated that the machine works a little more slowly than corresponds to the average interval between two arriving bottles. Furthermore there is provided on one of the eccentric sheaves mounted on and revolving with the shaft 59, on the sheave 91 for example, a short auxiliary contact 99, not shown, which still delivers current to the motor 55, after the pushing up and switching off of the mercury contact 52, until the half revolution of the shaft 59 is fully completed. If therefore in the time between the pushing up of the mercury contact 52 and the running off of the half revolution of the shaft 59 a bottle arrives upon the feeding conveyor 42 and releases the catch 43, the charging machine continues to run without interruption.

There is however no objection to a small supply of about two or three bottles accumulating upon the feeding conveyor 42, since the waiting time only amounts to a few seconds. In this case a bottle is always ready, after being freed by the pawl lever 49, 51, to release the catch 43 at the right time, so that a stoppage of the machine only occurs when the operating of the glass furnace is interrupted. It is advisable in this case, in order to render any supervision unnecessary, to provide above the resting position of about the third of the bottles accumulated upon the feeding conveyor 42, a thermo-couple 100, or any other contact actuated by the recumbent bottle, in the neighbourhood of the bottle body, as a result of which, through the medium of a relay for instance, more current is immediately supplied to the motor 55, and its speed of revolution thereby increased, so that the number of bottles accumulated upon the feeding conveyor 42 is quickly reduced to two again.

A special advantage of the machine is its rapid adjustability to different sorts of bottles and its adaptability to annealing furnaces of different breadths. To adjust the aggregate angle of oscillation of the distributor arms to the width of a particular annealing leir the moment of retraction and reversal of swing must be altered. Retraction obviously takes place twice for every revolution of the cam disc 61 or 61a; and reversal takes place at the same moment owing to the shifting of the dog clutch 76 or 76a by the cam disc 62a or 62; the cam discs 61 and 62 being mounted fast upon the sleeve 60, and the cam discs 61a and 62a upon the sleeve 60a. It is therefore necessary to alter the transmission ratio between the shaft 59 and the sleeves 60 and 60a.

In order to enable this transmission ratio to be easily altered, the two wheels a and b pertaining to the transmission gear 68, 68a are made readily accessible and exchangeable on the outside of the machine frame 1.

As soon as this charging machine has been definitely adopted in practice, the forward feeding of the annealing furnace belt conveyor 56 will doubtless be made controllable by the charging machine, since only by this means is an absolutely complete utilization of the space available for annealing ensured.

What I claim is:—

1. A machine for conveying and charging bottles and the like into an annealing furnace, comprising a substantially horizontal distributor arm projecting into the annealing furnace, a transporting track on the distributor arm, a tipping trough oscillatably suspended at the end of the distributor arm that projects into the furnace, the tipping trough being adapted to receive a bottle from the transporting track and to deposit the bottle without shock in an upright position in its allotted place in the annealing furnace, a pair of pivotally mounted wings adapted when closed to hold the bottle on the tipping trough and means for opening the wings after the bottle has been deposited. 15

2. A machine for conveying and charging bottles and the like into an annealing furnace comprising a substantially horizontal distributor arm projecting into the interior of the annealing furnace, a transporting device on the distributor arm, an oscillatable depositing device suspended on the end of the distributor arm that projects into the furnace, a flap mounted in the path of the bottles and adapted to be deflected by every bottle that passes on to the distributor arm, an electrical contact adapted to be closed by the deflection of the flap, electro-magnetic coupling means through which the depositing device is actuated, the said coupling means being adapted 20 to be energized by the closing of the said contact, and means for automatically de-energizing the said coupling means as soon as the bottle has reached the annealing furnace. 25

3. A machine for conveying and charging bottles and the like into an annealing furnace comprising a substantially horizontal distributor arm projecting into the interior of the annealing furnace, a transporting device on the distributor arm, an oscillatable depositing device suspended 30 on the end of the distributor arm that projects into the furnace, a feeding conveyor for bringing the bottles to the transporting device, a locking device fitted in the path of the bottles just above the feeding conveyor, a flap mounted in 35 the path of the bottles immediately in front of the locking device and adapted to be deflected by every bottle that passes on to the distributor arm, the locking device and flap co-operating with one another to prevent more than one bottle from 40 passing on to the transporting device of the distributor arm at the same time, an electrical contact adapted to be closed by the deflection of the flap, electro-magnetic coupling means through 45 which the depositing device is actuated, the said coupling means being adapted to be energized by the closing of the said contact, means for automatically de-energizing the said coupling means as soon as the depositing device has deposited the bottle in the annealing furnace, and an auxiliary contact adapted to come transiently into operation, to continue the supply of current to the coupling means notwithstanding the action of the automatic de-energizing means, thereby enabling the electro-magnetic coupling means to 50 remain closed until, if there is another bottle on the feeding conveyor, this bottle has had time to release the locking device, deflect the flap and re-close the first-mentioned electrical contact. 55

4. A machine for conveying and charging bottles and the like into an annealing furnace comprising a substantially horizontal distributor arm projecting into the interior of the annealing furnace, a transporting device on the distributor arm, an oscillatable depositing device suspended 60 on the end of the distributor arm that projects into the furnace, a feeding conveyor for bringing the bottles to the transporting device, a locking device fitted in the path of the bottles just above the feeding conveyor, a flap mounted in 65 the path of the bottles immediately in front of the locking device and adapted to be deflected by every bottle that passes on to the distributor arm, the locking device and flap co-operating with one another to prevent more than one bottle from 70 passing on to the transporting device of the distributor arm at the same time, an electrical contact adapted to be closed by the deflection of the flap, electro-magnetic coupling means through 75 which the depositing device is actuated, the said coupling means being adapted to be energized by the closing of the said contact, means for automatically de-energizing the said coupling means as soon as the depositing device has deposited the bottle in the annealing furnace, and an auxiliary contact adapted to come transiently into operation, to continue the supply of current to the coupling means notwithstanding the action of the automatic de-energizing means, thereby enabling the electro-magnetic coupling means to remain closed until, if there is another bottle on the feeding conveyor, this bottle has had time to release the locking device, deflect the flap and re-close the first-mentioned electrical contact. 80

on the end of the distributor arm that projects into the furnace, a feeding conveyor for bringing bottles to the transporting device, electrical driving means for the machine, and automatic switching means including a thermo-couple adapted to be actuated when bottles are accumulating upon the feeding conveyor and to supply more current to the electrical driving means and thereby accelerate the conveyance and depositing of the bottles.

5. A machine for conveying and charging bottles and the like into an annealing furnace, comprising a distributor arm projecting into the annealing furnace and oscillatable in a horizontal plane, a transporting device on the distributor arm, a depositing device oscillatably suspended at the end of the distributor arm that projects into the furnace, the depositing device being adapted to receive a bottle from the transporting device, oscillate forward into an upright position, and deposit the bottle without shock in an upright position in its allotted place in the annealing furnace, means including a worm for rocking the distributor arm through an angle, means for intermittently rotating the worm, and means for varying the angle through which the worm is rotated each time and thereby varying the angle through which the distributor arm swings after depositing one bottle and before depositing the next, according to the diameter of the bottles to be deposited.

6. A machine for conveying and charging bottles and the like into an annealing furnace, comprising a distributor arm projecting into the annealing furnace and oscillatable in a horizontal plane, a transporting device on the distributor arm, a depositing device oscillatably suspended at the end of the distributor arm that projects into the furnace, the depositing device being adapted to receive a bottle from the transporting device, oscillate forward into an upright position, and deposit the bottle without shock in an upright position in its allotted place in the annealing furnace, a rotatable worm for effecting the lateral oscillation of the distributor arm, a double clutch for reversing the direction of rotation of the worm, a cam adapted to shift the clutch, and gearing of variable transmission ratio driving the cam, this gearing enabling the aggregate angle through which the distributor swings to be adjusted according to the breadth of the annealing leir.

7. A machine for conveying bottles into an annealing leir comprising a substantially horizontal and laterally oscillatable distributor arm projecting into the interior of the leir, a conveyor adapted to convey bottles longitudinally along the distributor arm, and a depositing device attached to the end of the arm that projects into the leir, the said depositing device comprising a pair of vertical side plates, a tipping frame tiltably mounted in the side plates, means for positively tilting the tipping frame relatively to the side plates, a trough so mounted on the tipping frame as to receive a bottle in a horizontal position from the conveyor and to tilt with the tipping frame and with the

bottle into a vertical position, a pair of pivotally mounted wings adapted when closed to hold the bottle on the trough, means for opening the wings and sliding the trough and the bottle forward in the longitudinal direction of the distributor arm, and means for retracting the trough and rocking it back into its horizontal receiving position.

8. A machine for conveying bottles into an annealing leir and depositing them upon a continuously advancing leir conveyor, comprising a base, a slide longitudinally displaceable upon the base in the direction of movement of the leir conveyor, a substantially horizontal laterally oscillatable distributor arm mounted upon the slide, a conveyor adapted to convey bottles longitudinally along the distributor arm, a depositing device at the end of the distributor arm, occupying a position immediately above the leir conveyor, means for oscillating the distributor arm through such an angle that the depositing device moves from one side of the leir conveyor to the other, means for longitudinally advancing the slide in the same direction and at the same speed as the leir conveyor during the lateral oscillation of the distributor arm and means for suddenly retracting the slide when the distributor reaches each end of its lateral oscillation.

9. A machine for conveying bottles into an annealing leir and depositing them upon a continuously advancing leir conveyor as claimed in claim 8, further comprising means for adjusting the amplitude of the longitudinal advance of the slide.

10. A machine for conveying and charging bottles into an annealing leir comprising a substantially horizontal and laterally oscillatable distributor arm projecting into the leir, a conveyor adapted to convey bottles longitudinally along the distributor arm to the leir, a depositing device attached to the end of the distributor arm, the depositing device being adapted to receive a bottle from the transporting device, oscillate forward into an upright position, and deposit the bottle without shock in an upright position in its allotted place in the leir, and then return to its receiving position for the next bottle, means for swinging the distributor arm sideways through a distance equal to about the diameter of one of the bottles between the deposition of two successive bottles, a driving shaft for rocking the depositing device forward and backward and swinging the distributor arm laterally, motor means for driving the machine, an electro-magnetic clutch through which the said driving shaft is rotated by the said motor means, a flap mounted in the path of the bottles and adapted to be deflected by every bottle that passes on to the distributor arm, an electrical contact adapted to be closed by the deflection of the flap, the electro-magnetic clutch being adapted to be energized and thereby closed by the closing of the said contact, and means for automatically de-energizing and thereby opening the said clutch after the depositing device has deposited a bottle and returned to its receiving position.

HEINRICH SEVERIN.
